UNITED STATES PATENT OFFICE.

LOUIS KELLNER, OF NEW YORK, N. Y.

ELECTRIC SWITCH.

1,354,762.

Specification of Letters Patent.

Patented Oct. 5, 1920.

Original application filed December 3, 1917, Serial No. 205,139. Divided and this application filed May 8, 1919. Serial No. 295,655.

To all whom it may concern:

Be it known that I, LOUIS KELLNER, a citizen of the United States, and a resident of the borough of Manhattan, city, county, and State of New York, have invented certain new and useful Improvements in Electric Switches, (Case I,) of which the following is a specification.

This invention relates to improvements in 10 manually operable electric switches of the fused type. This application is a division of my co-pending application Serial No. 205,139, filed December 3, 1917.

The invention has for one of its objects 15 the provision of a fused switch so constructed that access to the fuse or fuses, or live parts is impossible except when the switch has been operated through the medium of its operating handle to break the 20 circuit.

A further object of the invention is to provide fuse-inclosing means having a hinged section and shiftable with the movable contacts of a switch relatively to a 25 stationary abutment to a position in which an opening movement of the hinged section will be prevented by said abutment when the movable contacts are in "on" position.

Another object of the invention is to provide 30 a switch having an inclosing casing divided into two compartments by an intermediate partition having an opening therethrough, the operating handle of the switch being located in the outer compartment and the 35 movable and stationary contacts being located in the inner compartment, and fuse-inclosing means movable with the movable contacts and having hinged cover sections held against movement by the edges of said 40 opening in the partition when the movable contacts are in "on" position, and shiftable into the outer compartment when the contacts are in "off" position to permit opening of said sections.

Another important object of the invention 45 is to provide fuse-inclosing means movable with the movable contacts of a switch and having a movable section or closure, and means adapted to prevent opening movement of the closure when the movable contacts are in "on" position and to automatically move said closure to closed position when the switch is operated to close the circuit without first closing said movable section or closure.

In the drawings, Figure 1 is a longitudinal sectional view of the switch taken on the line I—I of Fig. 4;

Fig. 2 a sectional plan taken on the line II—II of Fig. 1;

Fig. 3 a longitudinal section on the line III—III of Fig. 4, the parts being shown in position to close the circuit;

Fig. 4 a vertical central transverse section, the parts being shown in position to 65 break the circuit;

Fig. 5 a fragmentary sectional plan taken through the fuse box;

Figs. 6, 7 and 8 are fragmentary sectional views showing the positions assumed by the 70 operating mechanism when the switch lever has been moved to break the circuit, when the lever is in an intermediate position, and when the lever has been moved to close the circuit, respectively;

Fig. 9 a fragmentary vertical section showing the rack and segment for shifting the reciprocal switch member;

Figs. 10 and 11 detail views of a part of 80 the operating mechanism;

Figs. 12, 13 and 14 detail views of another part of the operating mechanism, and

Fig. 15 a top plan view of the fuse-inclos- 85 ing means.

Referring to the various parts by numerals, the switch is mounted on a suitable base 1, which may be formed of porcelain or other suitable material, and the entire switch mechanism is inclosed within a box-like outer casing, preferably formed of sheet 90 metal and held to the base 1 in any suitable manner. The casing is formed with side walls 2, end walls 3, and a cover 4 hinged to one of the end walls at 5.

Two vertically extending frame members 95 or plates 6 and 7 are held at their lower ends substantially centrally of the base 1, said members being preferably connected by an integral base plate 8 fastened upon the upper face of the base 1 by suitable 100 screws 9. The frame plates 6 and 7 are connected adjacent their upper ends by a rod 10 on which is rotatably mounted a sleeve 11 having reduced angular end por- 105 tions 12 and 13. The sleeve 11 is adapted to be oscillated by a swinging switch handle or lever 14 having an angular opening or socket through which the reduced end portion 12 of the sleeve extends. A disk 15 is mounted on the reduced angular end por- 110

tion 13 of sleeve 11, said disk being formed with a central angular opening 16 through which said end portion 13 extends to adapt the disk to rotate with said sleeve. The disk 15 is cut away through slightly more than half its periphery to from stop shoulders 17 and 18 adapted to abut against the free end of a pivoted arm or latch 19 when the switch lever is swung to the limit of its throw to break and close the circuit, respectively. The latch 19 is pivotally held at 20 to a lug 21 stamped inwardly from the frame plate 6, and is normally pressed upwardly in the path of the stop shoulders 17 and 18 by a suitable flat spring 22 held to the frame member 6.

A disk 23 is loosely mounted on the rod 10 adjacent the outer face of disk 15, and a mutilated gear wheel or segment 24 is held to the outer face of disk 23 to rotate therewith by means of suitable pins or rivets 25. The teeth of the gear wheel 24 mesh with the teeth of a rack 26 formed at one side of a vertically extending elongated opening 27 in a bracket 28. The bracket or plate 28 is held at its lower end by screws 29, to the upper face of a reciprocable block 30 formed of insulating material. The block 30 and bracket 28 are guided vertically, the block being provided with openings 31 through which the frame plates 6 and 7 extend, and the bracket being provided with an outwardly projecting pin or lug 32 working in an elongated slot 33 formed in the frame plate 7. The pin 32 serves also to limit the upward movement of the block 30 and the parts mounted thereon.

A spring 34 is coiled about the sleeve 11 and the opposite ends 35 and 36 of said spring project outwardly at one side of the sleeve in different horizontal planes. The switch lever 14 is provided with an inwardly projecting pin 37 extending between the ends 35 and 36 of spring 34, and the disk 23 is provided with an oppositely projecting pin 38 extending between the ends of said spring. The disk 23 is cut away through slightly more than half its periphery to form stop shoulders 39 and 40 adapted to engage latch 19 in the same manner as shoulders 17 and 18 of disk 15, and said disk 23 is also formed with oppositely disposed notches 41 and 42 in which the upper edge of latch 19 is adapted to engage to hold the disk 23 against rotation until the latch is released as hereinafter described. The latch 19 is adapted to be disengaged from notch 41 and notch 42 by the inclined or cam-shaped ends 43 and 44 of an arcuate oscillating releasing member 45 pivotally held at 46 to the inner face of disk 15. The disk 15 is provided with two lugs or stop pins 47 and 48 and the arcuate releasing member 45 is adapted to be rocked about its pivot 46 and held against said stop pins

alternately to alternately project the cam ends 43 and 44, respectively, beyond the periphery of the cut-away portion of disk 15 in position to depress latch 19 and disengage said latch from notches 41 and 42 in disk 23, as hereinafter described. The member 45 is adapted to be held against either of the stops 47 and 48 by a flat spring 49 held at one end to disk 15 in any suitable manner and formed with an offset portion 50 adapted to engage against opposite sides of a projection 51 formed on the member 45 adjacent the pivot 46 of said member.

A pair of fuse plugs 52 of well-known construction are supported on the block 30, the opposite ends of said plugs being detachably held in two pairs of suitable spring metal clips 53 and 54. Two pairs of contact brushes 55 and 56 are held to the under side of block 30 and electrically connected with the pairs of fuse-holding clips 53 and 54, respectively, by screws or bolts 57 and 58, the ends of the brushes preferably fitting in cut-away portions of the block 30, as shown. The outer ends of the brushes 55 are adapted to engage with contacts 59 held to the base 1, and the ends of brushes 56 are adapted to engage contacts 60 held to said base to complete the circuit through the switch when block 30 is depressed, as hereinafter described.

The fuse plugs 52 are inclosed within an inner casing or fuse box formed by the block 30 and two cover sections 61 and 62 which are hinged to rods 63 and 64 supported in the opposite ends of a pair of bars 65, preferably countersunk in opposite sides of block 30 and held thereto by screws 66. The hinged sections 61 and 62 of the fuse box are slotted at 61^a and 62^a, respectively, to clear plates 6 and 7 and bracket 28, and the meeting edges of said sections are cut away between said slots at 61^b and 62^b, respectively, to clear spring 22. These cover sections of the fuse box may be provided with interlocking portions or latches 67, if desired. The outer casing is divided into inner and outer compartments by an intermediate partition 68 having a rectangular central opening 69 therein to permit movement of the fuse box through said partition when the switch lever 14 is operated, as more fully hereinafter described.

To operate the switch to close the circuit, the switch lever 14 is swung through an arc of substantially 180° from the position shown in Figs. 1 and 2 to the position shown in Fig. 3. Referring more particularly to Figs. 6 to 9, it will be observed that as the lever 14 is thrown over, the sleeve 11 and disk 15 are rotated in a clockwise direction while disk 23 is held stationary by latch 19 which is engaged in notch 41 in disk 23, and it will also be seen that spring 34 is wound or placed under tension by pin 37

on lever 14, which forces the end 35 of said spring before it as the lever is swung to the right. It will be observed also that the inclined or cam end 44 of releasing member 45 is in projected position with its rear face 44^a in position to engage latch 19 during the initial movement of the switch handle. As the rear face 44^a rides over latch 19 the releasing member 45 will be rocked about its pivot 46, as spring 22 is stronger than spring 49, thus forcing the projection 51 to the opposite side of projection 50 on spring 49, retracting cam end 44 and projecting cam end 43 beyond the periphery of disk 15 in position to engage latch 19 and depress the same when the switch handle approaches the limit of its throw. As the lever 14 approaches the limit of its throw the inclined end 43 of releasing member 45 20 engages latch 19, as shown in Fig. 7, depressing said latch and releasing disk 23 which is rapidly rotated in a clockwise direction by reason of the engagement of the end 36 of spring 34 under pin 38 on disk 25 23. The rapid movement of disk 23 imparts a similar rapid semi-revolution to the mutilated gear or segment 24 meshing with rack 26, thus rapidly projecting or forcing bracket 28, block 30, and parts carried thereby, downwardly into the position shown in 30 Figs. 3 and 8, in which position the pairs of brushes 55 and 56 engage the pairs of contacts 59 and 60 and close the circuit through the switch. The latch 19 is preferably beveled at each side of its upper edge at the points where said latch is engaged by the cam ends of the releasing member 45 to form a cam surface 70 having its apex or highest point substantially centrally 40 of the upper edge of the latch. It will thus be seen that it is practically impossible for the switch lever to be held or to remain in a position to hold the latch 19 in its fully depressed or releasing position as the high 45 point or rear end of cam end 44 cannot be held or dwell upon the apex of the cam portion 70 of the latch. It will be seen, therefore, that the instant disk 23 is moved through half a revolution as above described 50 to force the laminated spring-metal contacts 55 and 56 into close engagement with the contacts 59 and 60, the latch 19 will snap into notch 42 in disk 23 and positively lock said disk against rotation.

55 At the completion of the circuit-closing operation just described the parts assume the position shown in Fig. 8, with the rear edge 43^a of cam end 43 projected into position to engage and ride over latch 19 during the initial movement of the switch handle toward the left to break the circuit. The circuit-breaking operation is the reverse of the operation just described and is thought to be obvious.

60 65 From the foregoing it will be observed that the switch lever may be swung substantially the full length of its throw without moving the brush-carrying block 30; that the movable contact member is operated with a rapid reciprocatory snap action 70 to close the circuit as well as to break the circuit; and that the entire switch mechanism is inclosed within a protecting casing.

It will also be seen that the fuse plugs are inclosed in a box or casing which is 75 shifted into the lower compartment of the switch casing when the circuit is closed, and that the fuse box is so constructed that the hinged covers or sections thereof cannot be swung upwardly to permit access to the 80 fuses when the circuit is closed, the false bottom 68 being so positioned as to prevent the hinged sections 61 and 62 of the fuse box from being swung upwardly and outwardly except when the switch is in "off" 85 position as shown in Figs. 1, 2 and 4, in which position the fuse box is projected above the false bottom or partition 68. It will be noted further that the switch cannot be moved to "on" position with the hinged 90 cover sections or closures of the fuse box in open position as said sections will be swung upwardly and inwardly to closed position when the block 30 moves downwardly by reason of the engagement of the partition 95 68 with the end walls of said sections, as indicated in dotted lines in Fig. 1. The cover 4 of the outer casing may also be provided with a suitable locking means to prevent unauthorized access to the switch 100 lever 14, if desired.

What I claim is:

1. In an electric switch, the combination of stationary contacts, a movable support, circuit-closing means mounted on said support and embodying a pair of contacts and a fuse connected with said contacts, means for moving said support to shift the contacts thereon into and out of engagement with the stationary contacts, fuse inclosing means 105 on said support having a section movable relatively to the support to permit access to the fuse when the circuit is open, and stationary means located at one side of the path of movement of the support adapted to hold the movable section of the fuse-inclosing means against an opening movement when the circuit is closed.
2. In an electric switch, the combination of stationary contacts, movable contacts, a 110 fuse electrically connected with said movable contacts, a stationary outer casing, a casing inclosing the fuse and its connections with the movable contacts having a hinged section, a partition dividing the outer cas- 115 ing into compartments and having an opening therethrough, and means for moving the fuse and its casing in unison with the movable contacts toward and from the stationary contacts to open and close the circuit, 120
3. In an electric switch, the combination of stationary contacts, movable contacts, a 125 fuse electrically connected with said movable contacts, a stationary outer casing, a casing inclosing the fuse and its connections with the movable contacts having a hinged section, a partition dividing the outer cas- 130 ing into compartments and having an opening therethrough, and means for moving the fuse and its casing in unison with the movable contacts toward and from the stationary contacts to open and close the circuit,

- said fuse-inclosing casing moving through the opening in said partition to carry the hinged section thereof from a position wholly within one compartment of the outer casing to a position in which an opening movement of said section will be prevented by said partition.
3. In an electric switch, the combination of an inclosing casing divided into inner and outer compartments by an apertured partition, stationary contacts in said inner compartment, a movable support, contacts carried by said support, a fuse carried by said support and electrically connected with the contacts on said support, and means located in the outer compartment of said casing for moving said support to make and break the circuit and to shift the fuse through the aperture in said partition from an accessible position in the outer compartment when the circuit is broken to an inaccessible position within the inner compartment when the circuit is closed.
4. In an electric switch, the combination of stationary contacts, a movable fuse box having hinged sections, a fuse therein, contacts connected with said fuse and movable therewith toward and from the stationary contacts, and means adapted to embrace the fuse box and prevent opening of the hinged sections thereof when the circuit is closed.
5. In an electric switch, the combination of stationary contacts, a movable support, contacts carried by said support, a fuse carried by said support and electrically connected with the contacts thereon, inclosing means for the fuse mounted on said support and movable relatively thereto to cover and uncover the fuse, means for moving said support toward and from the stationary contacts to make and break the circuit, and means adapted to hold the fuse-inclosing means against movement relative to the support when the support is moved to close the circuit to prevent access to the fuse.
6. In an electric switch, the combination of an inclosing casing having a cover, a partition dividing said casing into inner and outer compartments and formed with an opening therethrough, stationary contacts in said inner compartment, a support movable toward and from said stationary contacts, contacts held to the inner side of said support, a fuse carried by said support and electrically connected with the contacts thereon, a fuse-inclosing cover comprising hinged sections held to the outer side of said support, means located in the outer compartment of said casing for moving said support toward and from the stationary contacts to make and break the circuit, said fuse-inclosing cover being adapted to pass through the opening in said partition to place said cover above or below said partition to permit said hinged sections of the cover to be opened when the circuit is broken and to prevent said sections from being opened when the circuit is closed.
7. In an electric switch, the combination of stationary contacts, a movable support, contacts carried by said support, a fuse carried by said support and electrically connected with the contacts thereon, inclosing means for the fuse mounted on said support and movable relatively thereto to cover and uncover the fuse, a pivoted switch lever, operating connections between said lever and support for moving said support toward and from the stationary contacts with a rapid snap action as said lever approaches the opposite limits of its throw, and means adapted to prevent movement of said fuse-inclosing means relative to said support when the support is in circuit-closing position.
8. In an electric switch, the combination of stationary terminals, a movable fuse box comprising hinged sections, a fuse therein, contacts connected with said fuse and movable therewith toward and from the terminals, and means for preventing movement of the fuse-box toward the terminals with its hinged sections in open position, said means being adapted to automatically close said sections and to prevent opening thereof when the circuit is closed.
9. In an electric switch, the combination of stationary contacts, a fuse box having a movable closure portion, a fuse in said box, contacts connected with said fuse and movable with said box, means for shifting the movable contacts and the fuse box to make and break the circuit, and a stationary member adapted to prevent an opening movement of the closure portion of the fuse box when the movement contacts are in engagement with the stationary contacts.
10. In an electric switch, the combination of stationary contacts, movable contacts, a fuse, a fuse box movable with the movable contacts and having a hinged cover section, a stationary member, means for shifting the movable contacts and fuse box relatively to said member to make and break the circuit and to move the hinged cover section into and out of engagement with the stationary member.
11. In an electric switch, the combination of stationary contacts, movable contacts, a fuse, a fuse box movable with said contacts and having a hinged cover section, a casing inclosing the stationary and movable contacts having an opening in one wall thereof, an operating handle, and means controlled by said handle for shifting the movable contacts and the fuse box to make and break the circuit and move the hinge of said cover section toward and from one edge of the opening in the casing.
12. In an electric switch, the combination of stationary contacts, movable contacts, a

5 fuse, a fuse box having a movable closure, a switch handle, means controlled by said handle for moving said fuse box and the movable contacts in unison and automatically locking the same in their "on" and "off" positions, and a stationary member adapted to prevent movement of said closure when the movable contacts are in "on" position and to automatically force said 10 closure to closed position upon an operation of the switch handle to close the circuit when said closure is in open position.

13. In an electric switch, the combination of a casing having a wall formed with 15 an opening, stationary contacts in said casing, a support shiftable relatively to said wall, movable contacts mounted on said support, a fuse mounted on the support, fuse-inclosing means mounted on said support having a hinged section, and a switch handle operatively connected to shift said support to move the movable contacts into and out of engagement with the stationary contacts and move the hinged section of the 25 fuse-inclosing means relatively to the opening in said wall of the casing to and from a position in which said wall will prevent opening of said section.

14. In an electric switch, the combination 30 of a casing having a wall formed with an opening, stationary contacts in said casing, a support shiftable relatively to said wall, movable contacts mounted on said support, a fuse mounted on the support, fuse-inclosing means mounted on said support having a hinged section, and a switch handle operatively connected to shift said support to move the movable contacts into and out of engagement with the stationary contacts and 35 move the hinged section of the fuse-inclosing means relatively to the opening in said wall of the casing to and from a position in which said wall will prevent opening of said

section, said hinged section being so disposed relatively to one edge of said opening 45 that said section will engage the same and be shifted to closed position upon an operation of the handle to close the circuit with said section in open position.

15. In an electric switch, the combination 50 of a casing having a wall formed with a rectangular opening therein, stationary contacts within the casing, a support shiftable relatively to said wall, movable contacts mounted on the inner side of said support, a 55 fuse mounted on the outer side of said support electrically connected with the movable contacts, fuse-inclosing means mounted on the outer side of the said support having a hinged section located outside of said wall 60 with its hinge adjacent one edge of the opening in said wall when the movable contacts are in "off" position, said inclosing means being movable with said support to shift the hinge of the movable section to a point at the 65 inner side of said wall and to bring an intermediate portion of said section adjacent one edge of the opening in said wall when the movable contacts are shiftable to "on" position, and manually operable means for 70 shifting said support.

16. In an electric switch, the combination 75 of line terminals, a movable support, terminal bridging means mounted on said support including a fuse, fuse-inclosing 80 means mounted on said support having a section movable to permit access to the fuse, means for shifting the movable support to open and close the circuit, and a stationary member adapted to prevent an opening movement of said movable section of the fuse-inclosing means when the circuit is closed.

In testimony whereof I hereunto affix my signature.

LOUIS KELLNER.
